By Attorney

UNITED STATES PATENT OFFICE

FRANCIS W. GIBSON, OF WEST ROXBURY, MASSACHUSETTS

CONTAINER

Application filed March 2, 1928. Serial No. 253,474.

My present invention relates to multiple unit containers of suspended series type and aims to provide a hanging stack of receptacles for vegetables or other articles.

While the purposes and usefulness of my containers are many and wide its household utility for domestic storage as in the case of vegetables is so illustrative that I refer particularly to it.

Such a use illustrates the need of a simple, handy container, capable of being nested for shipment or storage and of expansion or enlargement by additions to meet growing needs or developing system in use.

Such a container series I have illustrated in the accompanying drawings in which

Fig. 1 shows a characteristic arrangement of suspended stack

Fig. 2 a fragmentary section

Fig. 3 a view showing three nested units.

In the embodiment shown I have provided a series of unitary bins or containers each comprising a back wall 1 having at top and bottom oppositely turned lips 1' and 1².

Adjacent the top I provide keyhole openings by which the container may be supported or if at the head of a suspended stack may support the rest.

When so hung the back wall 1 will be vertical and so considered the front wall 2 which inclines toward it has an inward slant.

The front wall 2 is also of less height than the rear wall 1 so that the sides 3 which have downwardly inclined upper edges 3' make a rather quick departure from the horizontal and so clear the bottom 4 of any similar container from which it may be suspended.

Each bin is capable of supporting by its lower lip 1² another bin unit which may be engaged with it by its upper and outwardly hooked lip 1'.

The side walls 3 are of sufficient upward flare to provide for a nesting of the bin units for convenience in packing and storing.

The side walls 3 are preferably perforated for ventilation but such perforation is not carried to the bottom so that there will be no escape of earth or loosened particles as the bin units are readily separable and can be emptied and washed.

By reason of their construction each bin unit while a complete individual container in itself may become a part of a stack by simply engaging its upper edge of its back wall 1 with the lower edge of the bin above it. When so engaged the pressure resultant of the overhang of the front wall 2 keeps each bin individually and the stack as a whole against the wall, door or other surface on which the stack is hung.

The downward slant of the upper edge of the side wall 3 and the lowered upper edge of the front wall 2 gives ready access to each bin interior when in the suspended stack formation.

As above pointed out the load pressure of each bin gives an inward resultant to its bottom and any additional pressure as by hand contact in reaching in has a similar inward resultant. This keeps positive contact between its own bottom engagement with the top of the next lower bin and is resisted by the load resultant of the bin next above it.

The size of my bins may be varied for different needs and different uses. While referred to as vegetable bins that of course is merely illustrative of a use in fulfilment of a common need. Within the indicated limits proportions may be changed but the overbalance of the front for maintainance of interlock and wall pressure is of great advantage and the nesting is of obvious importance because while a purchaser may start with a single bin or purchase additional bin units from time to time, the nesting makes it possible for the purchaser to carry home several units at once, or to have them delivered or mailed with little necessary packing.

What I therefore claim and desire to secure by Letters Patent is:

1. A multiple suspension stack comprising similar detachable interchangeable upper and lower unit members, each unit comprising a bottom and a back wall, an outwardly hooked lip on the top of said back wall and an inwardly turned lip on the bottom of said back wall, a front wall of lesser height than said rear wall and having an inward slant, side walls uniting said back and front walls and having inclined upper edges whereby

ready access to interior of each unit is provided, the outwardly hooked lip on the top of the back wall of the lower unit adapted to engage the inwardly upturned lip on the bottom of the back wall of the upper unit whereby the pressure resultant of the overhang of the front wall holds the bottom of each unit against the structure from which the stack is hung and tends to prevent disengagement of said lip.

10 2. A multiple suspension stack comprising similar detachable interchangeable upper and lower unit members, each unit comprising a bottom and a back wall having at top and bottom oppositely turned lips, a front wall of lesser height than said rear wall and having an inward slant, side walls uniting said back and front walls and having inclined upper edges whereby ready access to interior 15 of each unit is provided, the lip on the top of the back wall of the lower unit adapted to engage the inwardly upturned lip on the bottom of the back wall of the upper unit whereby the pressure resultant of the overhang of the front wall holds the bottom of each unit against the structure from which the stack is hung and tends to prevent disengagement of said lip.

20 3. A multiple suspension stack comprising similar detachable interchangeable upper and lower unit members, each unit comprising a bottom and a back wall having at top and bottom oppositely turned lips, a front wall of lesser height than said rear wall, side 25 walls uniting said back and front walls and having inclined upper edges whereby ready access to interior of each unit is provided the lip on the top of the back wall of the lower unit adapted to engage the inwardly upturned lip on the bottom of the back wall of the upper unit whereby the pressure resultant of the overhang of the front wall holds the bottom of each unit against the structure from which the stack is hung and tends to prevent disengagement of said lip.

40 4. A multiple suspension stack comprising similar detachable interchangeable upper and lower unit members, each unit comprising a bottom and a back wall having at top and bottom oppositely turned lips, a front wall of lesser height than said rear wall and having an inward slant, side walls uniting said back and front walls, the lip on the top of the back wall of the lower unit adapted 45 to engage the inwardly upturned lip on the bottom of the back wall of the upper unit whereby the pressure resultant of the overhang of the front wall holds the bottom of each unit against the structure from which the stack is hung and tends to prevent disengagement of said lip.

In testimony whereof I affix my signature.

FRANCIS W. GIBSON.
